Primary Examiner — Deanna L Pratt(74) *Attorney, Agent, or Firm* — Knobbe, Martens, Olson & Bear, LLP(57) **CLAIM**

The ornamental design for a vanity mirror, as shown and described.

DESCRIPTION

FIG. 1 is a top, front, left-side perspective view of a vanity mirror embodying our design;

FIG. 2 is a top, rear, right-side perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.

All features in broken line form no part of the claimed subject matter.

1 Claim, 7 Drawing Sheets# US D845,652 S
